UNITED STATES PATENT OFFICE

135,295

DESIGN FOR A TOY

Thomas J. Parker, Oaklandon, Ind.

Application December 31, 1941, Serial No. 104,936

Term of patent 3½ years

To all whom it may concern:

Be it known that I, Thomas J. Parker, a citizen of the United States and resident of Oaklandon, in the county of Marion, State of Indiana, have invented a new, original, and ornamental Design for a Toy, of which the following is a specification, reference being had to the accompanying drawing, forming part thereof.

In the drawing, Figure 1 is a side view, and Figure 2 is a top plan view of a toy showing my new design.

I claim:

The ornamental design for a toy, as shown.

THOMAS J. PARKER.
